US0D1036672S

(12) **United States Design Patent** (10) **Patent No.:** **US D1,036,672 S**
(45) **Date of Patent:** **** Jul. 23, 2024**

(54) **PORTABLE IMAGING SYSTEM**

(71) Applicant: **Lazurite Holdings LLC**, Cleveland Heights, OH (US)

(72) Inventors: **Laimis Kazimieras Belzinskas**, Kirtland, OH (US); **Ilya Malinskiy**, Mayfield, OH (US); **Eugene Malinskiy**, Cleveland Heights, OH (US)

(73) Assignee: **Lazurite Holdings LLC**, Cleveland Heights, OH (US)

(**) Term: **15 Years**

(21) Appl. No.: **29/798,156**

(22) Filed: **Jul. 6, 2021**

(51) LOC (14) Cl. **24-01**

(52) U.S. Cl.

USPC **D24/158**

(57) **CLAIM**

The ornamental design for a portable imaging system, as shown and described.

DESCRIPTION

FIG. 1 is a top perspective view of a portable imaging system showing our new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines illustrate structure or features that form no part of the claimed design.

1 Claim, 7 Drawing Sheets
